MAGAZINE FOR SHUTTLE-BOBBINS FOR AUTOMATIC LOOMS

Application filed June 5, 1930, Serial No. 459,357, and in Switzerland June 14, 1929.

This invention relates to automatic looms and has for its object to provide an improved magazine for shuttle-bobbins for looms of this kind.

The invention relates more particularly to a magazine for shuttle-bobbins of the kind in which the boring of the bobbin serves as a guide for the shuttle thread. This magazine can be used on automatic looms having one or several shuttles.

10 The magazine according to the invention is distinguished by the feature that the shuttle thread runs to the thread holder from the heads of the bobbins supported in the magazine towards the end of the shuttle-race. 15 Preferably in the end of the bobbin head guide of the magazine an opening is provided through which the shuttle thread passes to the thread holder.

20 The accompanying drawings illustrate a constructional example of the invention, in which

Fig. 1 is an elevation;

Fig. 2 is a side view looking from the right of Fig. 1;

25 Fig. 3 is a side view from the left of Fig. 1;

Figs. 4 and 5 are two sections on the lines A—B of Fig. 3 and C—D of Fig. 2 respectively.

30 Referring to the drawings, the bobbin magazine 1 has a left guide 2 (Figs. 1, 3 and 4) for the conically shaped bobbin points 3 and a right hand guide 4 (Figs. 1, 2 and 5) for the bobbin-heads 5. The bobbin-head guide 4 which is U-shaped in cross section is 35 provided at the end with a slot opening 6 through which the shuttle thread beginnings 7 run to the thread holder 9 from the bobbin heads 5 towards the end of the shuttle-race 8. This arrangement facilitates a frictionless 40 supply of the shuttle thread beginnings into the shuttle, owing to the fact that the threads do not come in contact with the guide walls and bobbin flaps.

45 The guide 2 for the conical bobbin points 3 has a brake-device 10 located in front of a felt layer, for the thread windings on the bobbin points.

50 With shuttle material with high speed, for example twist for silk, artificial silk, cotton, and wool crêpe tissue, or texture, it easily

happens that owing to the longer path the back-slip and the vibration of the loom the windings become loose on the bobbin points and when running off form loops, which may produce errors and disturbances. The brake-device is adapted to ward off this disadvantage, in that it retards the thread cone of the bobbin tips in the direction of the winding-on of the thread.

The magazine is fixed in any desired manner from the frame of the loom.

55 What I claim is:—

A magazine for weft bobbins for automatic looms, the bores of the bobbins serving as guides for the weft threads, said magazine including a guide having an opening therein through which the thread ends extend from the heads of the bobbins through the magazine to the thread holder, and which lie in the surface generated by the bobbin, as it 60 gravitates towards transfer position.

65 In testimony whereof I affix my signature.

70 ERNST EGLI.
